[57] ABSTRACT

Driven rubber belts are arranged for receiving a roll of paper. A paper deflector is positioned to catch the free end of the rotating paper roll for guiding it through a paper feeding mechanism.

AUTOMATIC PAPER LOADING AND GUIDING MECHANISM

REFERENCE TO RELATED APPLICATION

This application is related to a portion of the subject matter of copending U. S. patent application Ser. no. 1,534,437 entitled IMPROVED PROGRAMMABLE CALCULATOR, filed on June 15, 1971, by Robert E. Watson, Jack M. Walden, and Charles W. Near and assigned to the same assignee as the present application.

BACKGROUND AND SUMMARY OF THE INVENTION

This invention relates generally to paper guiding mechanism and more particularly to an improved mechanism for automatically loading and guiding rolled paper.

Such mechanisms have been employed in various office machines and, more recently, in printing units associated with high-speed computers and desk top calculators. Most of these units require time consuming manual threading each time a roll of paper is inserted. It is desirable to supply a unit which automatically threads the free end of each roll as it is inserted. Those few units in the prior art which can automatically accommodate paper rolls are limited to one particular roll diameter. It is an advantage to be able to change paper types at will and to be able to reinsert, for example, a partially consumed roll. In addition, prior art units have, through the use of rollers in contact with paper, employed a pushing technique for guiding and feeding the paper, which is only successful in handling the heavier weights of paper. Printers associated with computers and desk top calculators must have the ability to accommodate many different types of paper in performing a variety of printing functions. A number of these units employ thermal means for printing characters, thus requiring the use of thermally sensitive paper which is characteristically thinner than those papers used with impact printers.

Accordingly, it is the principal object of this invention to provide an improved paper loading and guiding mechanism which will automatically thread the free end of a roll of paper along a desired path.

It is a further object of this invention to provide an improved paper loading and guiding mechanism which is capable of accommodating all commonly available thicknesses of printing papers and rolls of varying diameter.

These objects are accomplished in accordance with the preferred embodiment of this invention by employing two driven rubber belts for receiving a roll of paper and for making contact therewith at each edge thereof. A bucket for holding the paper roll during use is located above the belts. A paper guide and deflector member is positioned so as to be in contact with a front portion of each of the belts and so that an end portion of the deflector member protrudes into the bucket cavity for deflecting the free end of the roll into position for being guided by the belts.

DESCRIPTION OF THE DRAWINGS

FIG. 1 is a cross-sectional view of a printing unit which embodies the present invention.

FIG. 2 is a sectional view taken along the line A—A in FIG. 1 to show the relationship of the paper, belts, and paper guide and deflector member.

DESCRIPTION OF THE PREFERRED EMBODIMENT

The printer shown in FIG. 1 is symmetrical about the section line A—A and is of the type shown in the above mentioned copending patent application. Paper roll 12 is loaded into the printer by lifting bucket cover 13 and placing the roll in position for uprolling forward from the bottom. This bucket cover serves to keep the free end of the paper within bucket halves 3 and 8 during loading and, after loading, to prevent the free end from reloading itself through the mechanism. A belt 9 is provided at each edge of the paper and is driven by drive pulley 5 which is in turn driven by motor 11. A print head 1 is spring loaded against a driven platen 2 and is cammed away therefrom at the appropriate time during loading by a head lifter 4 to facilitate passage of the free end of the paper roll. The diameter and speed of the platen are such that its surface speed is approximately 5 percent faster than that of belts 9 to insure that the paper is maintained under tension after loading is completed. Drive pulley 5 and an associated rear idler pulley 10 are crowned so that the belts will be self-centering. An associated front idler pulley 7 is flat and is provided to maintain the lower portion of the belt away from the bucket area.

The weight of the paper stretches rubber belts 9, allowing the paper to roll forward until it rests against a paper guide 6. A downhill slope toward the paper guide is created by the placement of rear idler pulley 10. With the paper roll in this position and the belts moving, the free end of the paper is constrained by the belts 9, paper guide 6, and roll 12 to travel below the paper guide and between it and the belts. FIG. 2 illustrates a section through the paper guide showing the relative positions of the paper, belts, and paper guide. The paper is edge-guided through the mechanism during loading and subsequent operation. Ordinarily, paper does not lend itself to successful edge guiding due to its very low compressive strength. The present invention overcomes that problem by providing paper guide 6 with a convex bottom surface against which the paper is held by belts 9, under tension, thus preventing buckling of the paper.

In selecting materials for various parts of the loading mechanism it is important to maintain compatible coefficients of friction. The coefficient of friction between the paper and paper guide 6 should be low relative to that existing between the paper and belts in order that the belts can drive the paper through the mechanism. Similarly, the coefficient of friction between the paper and platen 2 should be high relative to that existing between print head 1 and the paper in order that the paper may be driven through the mechanism during printing. In addition, the drag introduced by the belts and paper guide due to the paper moving faster than the belts during printing must not be so great as to tear the paper or overload the motor.

I claim:

1. A mechanism for automatically loading and guiding paper from a roll, said mechanism comprising:
a paper holding bucket having an opening in the bottom end thereof;
a belt positioned adjacent to the opening in the bottom end of the bucket for receiving a roll of paper and for frictionally controlling movement of the roll;

a paper guide and deflector member having a deflector portion that protrudes into the cavity of the bucket and a guide portion that contacts the belt for constraining the paper to travel between the belt and the guide; and means for driving the belt.

2. A mechanism as in claim 1 wherein a pair of belts is positioned adjacent to the opening in the bottom of the bucket for contacting the paper roll near its edges.

3. A mechanism as in claim 1 further comprising a cover disposed over the top end of the bucket for keeping the free end of the paper inside the bucket during loading and for preventing the free end from reloading itself through the mechanism during subsequent operation.

4. A mechanism as in claim 1 wherein said paper

guide and deflector member has a convex surface for contacting the paper and belt so that the paper is strengthened by being constrained to follow a curved path.

5. A mechanism as in claim 2 further comprising a cover disposed over the top end of the bucket for keeping the free end of the paper inside the bucket during loading and for preventing the free end from reloading itself through the mechanism during subsequent operation.

6. A mechanism as in claim 2 wherein said paper guide and deflector member has a convex surface for contacting the paper and belts so that the paper is strengthened by being constrained to follow a curved path.

UNITED STATES PATENT OFFICE
CERTIFICATE OF CORRECTION

Patent No. 3,779,473

Dated December 18, 1973

Inventor(s) Roger C. Edrinn

It is certified that error appears in the above-identified patent
and that said Letters Patent are hereby corrected as shown below:

Column 1, line 7, change "1,534,437" to read --
153,437 --; line 15, change "mechanism" to read -- mechanisms --;
and line 42, change "provie" to read -- provide --.

Signed and sealed this 9th day of April 1974.
